United States Patent Office.

JOHN SCHOLL, OF SOHO, ASSIGNOR TO SAMUEL S. BATESON, OF MAYFAIR, ENGLAND.

Letters Patent No. 80,568, dated August 4, 1868.

IMPROVEMENT IN GAS-BURNER ATTACHMENTS.

The Schedule referred to in these Letters Patent and making part of the same.

TO ALL TO WHOM IT MAY CONCERN:

Be it known that I, JOHN SCHOLL, of Berwick street, Soho, in the county of Middlesex, England, engineer, have invented certain "Improvements in Gas-Burners, and in Apparatus to be Used in Connection therewith;" and I do hereby declare the following to be a full, clear, and exact description of the same.

This invention has for its object the protecting from injury the platinum and other like appliances which are sometimes fitted on to or over gas-burners, with a view to the improving the light obtained therefrom.

It has been found in practice that these gas-light improvers, which in some instances consist of a very thin and fragile strip of platinum, or other metal, placed across and standing up above the top of the burner, are liable to be broken or deranged accidentally, when removing the dust from the burner or adjacent parts.

In order to obviate this objection, I propose to combine with each gas-light improver, a metal or other guard, which will effectually protect it from injury, without, at the same time, casting any appreciable shadow. This guard may obviously be constructed and applied in various ways, with a view not only to protect the platinum light-improver, but also to maintain it securely in its proper adjusted position on the burner.

Figure 1 of the drawings is an elevation, and

Figure 2 a plan, showing, as an example, one mode of applying a guard to a fish-tail burner.

Figures 3, 4, and 5, are detached views of the guard-light perfecter and burner respectively.

a is the burner, having a platinum light-perfector, *b*, adapted thereto, protected by the guard *c*, the whole of the parts being shown adjusted ready for use in figs. 1 and 2.

The guard or protector *c* may consist of a piece of metal, bent into the form of a collar, and having, say, four protecting-fingers, *d d*, formed thereon, which fingers are slightly bent or curved inwards and outwards, so as to grip the top edge of the burner.

In the collar of the light-improver there are cut a number of slots, *e e*, corresponding to the fingers of the guard, so that when the guard is adjusted, the fingers *d* will spring into these slots, and bear against the burner itself.

In order to prevent the light-improver and guard from turning round on the burner, I grind, or otherwise produce, a number of flat faces or facets, *f*, on the circumference of the burner, at the top thereof, against which flat surfaces the fingers *d* obtain a bearing, and thereby prevent any tendency of the parts to move round the burner. It will be seen that the fingers *d* project slightly above the piece of platinum *b*, and thereby protect it from injury.

In lieu of holding the parts in position by cutting facets round the burner, the same effect may be obtained by having one or more stems or projections formed on the lower part of the guard, and fitting into slots made either in a separate shoulder, or into a shoulder made in one piece with the burners. This is clearly shown in Figures 6 and 7, where the ordinary burner *a* is screwed into a metal socket, which is itself screwed into the pipe, as shown in figs. 6 and 7. This socket *g* is formed with a shoulder or collar, *g'*, in the opposite sides of which are made two vertical slots, grooves, or perforations *h h*; or the shoulder containing the slots *h* may be made in one piece with the burner itself, as shown in Figure 8.

The guard or protector *c* to be used in this modification has two stems or strips *i i*, shown clearly in Figure 9, projecting from its lower edge, and is so situated as to correspond, when properly adjusted, with the slots *h*, into which they fit, as shown in the drawings. The guard is thus prevented from turning, and as its fingers *d* engage with the slots *e e*, in the collar of the light-improver, it follows that the latter will also be maintained in its proper place.

In the case of street and other lamps, which are sometimes lighted and extinguished by introducing an apparatus for the purpose through the bottom of the lamp, there would be some risk of pushing off the guard, and with it the perfecter, but this may be obviated by simply making the slots or holes *h h*, in the collar *g*, to

incline inwards towards the bottom, and nipping or pinching the lower ends of the stems *ii* after they have been inserted into the said slots or holes. By this means the guard will be effectually locked to the burner.

Claims.

1. The combination, with a platinum or other equivalent gas-light improver or perfecter, of a guard or protector, for the purpose hereinbefore set forth.
2. The peculiar modes of combining a gas-light improver or perfecter with a guard or protector, whereby the former is maintained, through the agency of the latter, in its proper adjusted position, substantially as hereinbefore described, and illustrated by the drawings.

In testimony whereof, I have signed my name to this specification in the presence of two subscribing witnesses.

JOHN SCHOLL.
